ENVELOPE ADAPTED TO BE ROUTED TO SEVERAL DESTINATIONS

Leonard P. Miner, Bridgeport, Conn., assignor to David E. Zimmer, Bridgeport, Conn.

Filed Mar. 16, 1959, Ser. No. 799,547

3 Claims. (Cl. 229—73)

This invention relates to reusable envelopes of the type employed by business houses for holding papers and the like, and more particularly to interoffice and similar envelopes which are intended to be routed to various people and destinations.

Heretofore interoffice business envelopes of the type adapted to be sent to a number of destinations have been generally constituted of strong and durable paper such as kraft paper or the like, said envelopes having openings in their body portions to enable a user to ascertain the presence or absence of any contents, and further having a number of address lines or blank spaces on which the various destinations may be inscribed, this being done preferably in pencil.

After such an envelope has reached its first destination and is to be forwarded to a second person or destination, the name of the first person or destination is either erased or struck through, so that the second person or destination may be set down or indicated as being the one next to receive the envelope.

Since envelopes of this type are intended to be used a number of times, and since they represent a certain amount of cost and value, the names and destinations inscribed on the envelopes are generally erased to prepare the envelope for subsequent use. While such procedure has been considered satisfactory it left something to be desired inasmuch as the envelopes would quickly begin to show signs of wear and deterioration, and further since the act of erasing or striking through the names caused the envelope to have an untidy and unbusinesslike appearance.

The present invention obviates the above disadvantages and drawbacks of prior interoffice, routing-type envelopes, and one object of the invention is to provide a novel and improved envelope of this type wherein the names of persons and destinations may be very easily and quickly erased or removed with a minimum of time and difficulty, thereby to facilitate and make more convenient the use of the envelope.

A further object of the invention is to provide an improved interoffice routing-type envelope as above set forth, which will always be neat and businesslike in its appearance regardless of erasures or changes in names of the persons and destinations.

Still another object of the invention is to provide an improved business envelope in accordance with the foregoing, wherein the direction-providing means may be so organized as to permit its quick and easy removal and replacement, thereby enabling the useful life of the envelope to be extended.

A feature of the invention resides in the provision of a novel and improved business envelope as above characterized which is extremely simple in its construction and economical to fabricate and produce.

Another feature of the invention resides in the provision of an improved business-type envelope of the type set forth, which is reliable in its functioning and not likely to be easily rendered inoperative or useless.

2

Other features and advantages will hereinafter appear.

In the drawings accompanying this specification similar characters of reference have been used to designate like components throughout the several views, in which:

5 Figure 1 is a back view of an improved inter-office routing-type business envelope as provided by the invention, the flap of the envelope being shown as closed and also clasped to the envelope body portion.

10 Fig. 2 is a view like Fig. 1, but showing the flap of the envelope in open position.

Fig. 3 is a fragmentary back view of an envelope with its flap open, illustrating a modification of the invention.

Fig. 4 is a fragmentary sectional view, taken on the line 4—4 of Fig. 3.

Fig. 5 is a back view of an envelope having its flap open and made in accordance with the invention, illustrating another modification thereof.

Considering first the embodiment of the invention illustrated in Figs. 1 and 2, the improved routing-type busi-

20 ness envelope shown therein comprises a pocket-like body portion 10 which is adapted to hold papers and the like, in conjunction with a hinged flap 12 which is foldable against the body portion 10 for the purpose of retaining the papers therein in the usual manner.

25 The body portion 10 and hinged flap 12 may be formed from a single sheet of material as in the case of conventional envelopes, and the body portion may have a front panel 14 together with a plurality of roughly triangular-shaped rear panels 16, 17 and 18, the rear panels 30 being secured together along their marginal portions in the customary manner.

35 The envelope body portion 10 is provided with the usual perforations or through openings 20 to enable a user to readily determine if there are any contents in the envelope without opening the flap and actually peering into the body portion.

40 In accordance with the present invention, the envelope body portion 10 and flap 12 are provided with cooperable means by which directions for routing the envelope may be neatly provided at the back surface of the envelope, and whereby such directions may be easily and quickly eradicated or changed, all without adversely affecting the appearance and usefulness of the envelope or adversely affecting the useful life thereof.

45 Heretofore it has been the customary practice to provide on the front face or panel of the body portion of business envelopes a number of inscription lines or blanks adapted to be written on, to provide the directions for routing the envelope.

50 Customarily these directions have been either struck through or else erased as with a rubber or other eraser, when they are superseded by other, different directions. The striking through of the original directions or the erasing of the same leaves the envelope with an untidy or 55 somewhat messy appearance and often during the act of erasing using a rubber or equivalent eraser the envelope becomes wrinkled and deteriorates at a much faster rate than if no erasing whatsoever were to be done.

60 In accordance with the present invention, the hinged flap 12 and body portion 10 of the envelope have cooperable means for indicating directions, and as shown in Figs. 1 and 2 the flap 12 is provided with a transparent window through which an underlying area of the body portion 10 may be viewed when the flap 12 is in the 65 closed position of Fig. 1. Further, the body portion 10 of the envelope is provided with impressionable means which extends over the said underlying area and is adapted to have writing impressions formed on it, whereby the said impressions may be viewed through the said window.

65 70 In the embodiment of Figs. 1 and 2, the said cooperable means on the flap and body portion 12 and 10 respec-

tively comprise recording and pigmented elements of the type used in memorandum pads popularly known as "magic-erasing" pads. Considering Fig. 2, the envelope flap would be provided with a transparent, thin plastic sheet 22, whereas the envelope body portion 10 would be provided with an impressionable means in the form of a relatively stiff card-like member 24 having on its exposed surface a wax or wax-like composition of the type adapted to adhere at concentrated pressure points to the undersurface of the transparent plastic 22 when the plastic is written on by a suitable stylus or similar instrument.

As seen in Fig. 1, the inscription "J. A. Smith Room 123" has been written, as by the use of a stylus, on the transparent window 22, and the wax or wax-like substance of the element 24 has adhered to the undersurface of the window 22 so as to be readily visible from the back of the envelope.

As is well understood, upon separation of the window 22 from the underlying wax-coated element 24, the writing will "disappear" and by the present invention such separation is effected by merely separating the flap 12 from the envelope body portion 10 as by the act of opening the envelope to remove its contents.

Further, in accordance with the present invention, co-operable clasp means are provided on the flap 12 and envelope body portion 10, to prevent inadvertent or accidental opening of the flap. In Figs. 1 and 2, such clasp means comprises a tab 26 on the flap 12 and a slit 27 provided in the panel 16 of the body portion 10 for the purpose of accommodating the tab as seen in Fig. 1.

Thus, after the desired papers or other contents have been placed in the body portion 10 of the envelope, the flap 12 is folded down and the tab 26 engaged in the slit 27. Thereafter, a suitable inscription is "written" on the transparent window 22 by the use of the stylus as aforesaid, providing the necessary directions for routing the envelope. Upon the addressee receiving the envelope, the mere act of opening the same and removing the contents will automatically erase the inscription which has been previously placed on the transparent window 22. Thereafter, the said addressee in making use of the envelope again, will merely repeat the above-described operation of placing the desired matter in the body portion 10, closing and clasping the flap 12, and inscribing the necessary directions on the transparent panel 22.

It will be understood from the foregoing that I have provided a novel and improved business envelope of the type intended to be routed to a number of different people or destinations, wherein the routing directions may be easily and quickly erased, preferably automatically as a consequence of the act on the part of the recipient of the envelope, of opening the latter to remove the contents thereof. No erasing as by the use of a rubber or equivalent device is necessary at any time, and accordingly the neatness of appearance of the envelope may be always preserved. Moreover, there is no likelihood of the envelope becoming wrinkled and useless as a consequence of erasing or eradicating the directions which are no longer required. Therefore, envelopes made in accordance with the invention as above described may have an extended period of usefulness and will retain their original, neat appearance.

Another embodiment of the invention is illustrated in Figs. 3 and 4. As shown in these figures, the transparent window 22 and the wax-coated element or card 24 are carried by flat pockets 30 and 31 respectively, the said pockets being provided on the envelope flap 12a and envelope body portion 10a. The pockets 30 and 31 may be constructed in any desired manner, as from formed or embossed board or stiff paper, plastic composition and the like. By virtue of the openings of the pockets 30 and 31 adjoining the fold or crease line 33 of the envelope, there is no possibility of the elements 22

and 24 becoming displaced from the pockets during the time that the envelope is closed. Further, a snug or frictional fit may be provided between the elements 22, 24 and the respective pockets 30, 31, thereby to further retain the elements in place.

In the form of the invention illustrated in Figs. 3 and 4 the clasp means by which the flap 12a is retained in its closed position may comprise a nib or projection 35, provided on a flat arm 36 extending from the pocket 31, and 10 may further comprise a second flat arm 38 provided on the pocket 30 and having a slot 39 formed with an enlarged central portion 40 which latter is adapted to accommodate and frictionally seize the nib 35 of the arm 36 when the flap 12a is closed.

Another embodiment of the invention is illustrated in Figs. 5 and 6. In this form the envelope body 10b and the flap 12b are preferably reinforced with suitable marginal wire frames 42 and 43, the frame 43 having a U-shaped handle 44 cooperable with a clasp eye 45 to retain the flap 12b in its closed position. The flap 12b 20 has a transparent plastic window 22, through which the directions may be viewed.

In this form of the invention, the pocket 31b on the body portion 10b carries a writing pad 24b consisting of a number of sheets of writing paper secured or bound together in padded form. The pad 24b is intended to be written on by a usual writing instrument such as a pencil or pen, and when the routing directions are to be changed, the uppermost sheet of the pad 24b is stripped or torn off, and the new directions are inscribed on the next sheet, and so on. When the flap 12b is closed, the plastic window 22 will protect the writing on the pad 24b, and as with the other forms of the invention, the envelope will at all times retain its neat appearance, and 30 will not be wrinkled or otherwise deformed by an erasing procedure utilizing a rubber or equivalent device, since such procedure is not required. Instead, it is merely necessary for the user to remove or strip off the top used sheet from the pad 24b, and provide the new directions on the fresh underlying sheet. When the pad 40 24b is completely consumed, a new pad may be readily substituted in the pocket 31b.

It will now be understood from the foregoing that, in accordance with my invention I have provided a novel and improved interoffice routing-type business envelope 45 wherein the routing directions may be easily and quickly erased and replaced by new directions while the envelope at all times retains its original, appearance. In the forms of Figs. 1-4, the mere act of opening the envelope and removing the contents automatically erases the inscription, whereas in the form of Fig. 5, the user need merely remove the uppermost sheet of the pad 24b each time. The present improved envelope is simple in its construction and may be readily economically fabricated in quantity.

55 Variations and modifications may be made within the scope of the claims, and portions of the improvements may be used without others.

I claim:

1. An envelope of the type intended to be routed to 60 various people, said envelope having a pocket-like body portion adapted to hold papers and the like, and having a hinged flap foldable against the body portion; and a pair of cooperable recording and pigmented elements on the said flap and body portion respectively, providing a self-erasing writing means on which writing may be produced and retained while the flap is disposed against the body portion, said writing being automatically erased upon separation of the flap from the body portion, said hinged flap and body portion respectively having pockets holding 65 the said cooperable elements to enable the latter to be easily and quickly removed and replaced.

2. An envelope of the type intended to be routed to 70 various people, said envelope having a pocket-like body portion adapted to hold papers and the like, and having a hinged flap foldable against the body portion; and a

pair of cooperable recording and pigmented elements on the said flap and body portion respectively, providing a self-erasing writing means on which writing may be produced and retained while the flap is disposed against the body portion, said writing being automatically erased upon separation of the flap from the body portion, the cooperable element carried by the flap comprising a sheet of transparent plastic, and the cooperable element carried by the body portion comprising a member having a wax-like coating arranged to adhere to the underside of the plastic sheet in the form of a writing impression when the plastic sheet is written on.

3. An envelope of the type intended to be routed to various people, said envelope having a pocket-like body portion adapted to hold papers and the like, and having a hinged flap foldable against the body portion; a pair of cooperable recording and pigmented elements on said flap and body portion respectively, providing a self-

10
5

erasing writing means on which writing may be produced and retained while the flap is disposed against the body portion, said writing being automatically erased upon separation of the flap from the body portion; and cooperable clasp means on the said body portion and flap, for releasably holding the flap in closed position against the said body portion.
